US0D1070774S

(12) **United States Design Patent** (10) **Patent No.:** **US D1,070,774 S**
(45) **Date of Patent:** **** Apr. 15, 2025**

(54) **RECEPTACLE ASSEMBLY PANEL**

(71) Applicant: **Yamaichi Electronics Co., Ltd.**, Tokyo
(JP)

(72) Inventor: **Toshiyasu Ito**, Tokyo (JP)

(73) Assignee: **YAMAICHI ELECTRONICS CO., LTD.**, Tokyo (JP)

(**) Term: **15 Years**

(21) Appl. No.: **29/854,883**

(22) Filed: **Sep. 28, 2022**

(51) **LOC (15) Cl.** **13-03**

(52) **U.S. Cl.**

(57) **CLAIM**

The ornamental design for a receptacle assembly panel as shown and described.

DESCRIPTION

FIG. 1 is a front, right and top perspective view of a receptacle assembly panel in accordance with my new design;

FIG. 2 is a front, right and bottom perspective view thereof; FIG. 3 is a top plan view thereof;

FIG. 4 is a bottom plan view thereof;

FIG. 5 is a left-side elevational view thereof;

FIG. 6 is a right-side elevational view thereof;

FIG. 7 is a front elevational view thereof; and,

FIG. 8 is a rear elevational view thereof.

The broken lines in the figures are directed to environment and are for illustrative purposes only; the broken lines form no part of the claimed design.

1 Claim, 8 Drawing Sheets
